INVENTOR
James W. Price,

BY *John H. Do.*
ATTORNEY

UNITED STATES PATENT OFFICE.

JAMES W. PRICE, OF TULSA, OKLAHOMA.

CHECK-PROTECTOR.

1,363,916.

Specification of Letters Patent. Patented Dec. 28, 1920.

Application filed June 17, 1920. Serial No. 389,688.

To all whom it may concern:

Be it known that I, JAMES W. PRICE, a citizen of the United States, and a resident of Tulsa, in the county of Tulsa and State 5 of Oklahoma, have invented certain new and useful Improvements in Check-Protectors, of which the following is a specification.

My invention is an improvement in check protectors, and has for its object to 10 provide a device of the character specified, wherein means is provided for defacing a check or the like at predetermined points in such manner that erasures cannot be made without showing plainly that the check has 15 been tampered with.

In the drawings:

Figure 1 is a top plan view of the improved tool, with a part broken away,

Fig. 2 is a perspective view of the upper 20 or movable member,

Fig. 3 is a bottom plan view of the improved tool,

Fig. 4 is an edge view,

Fig. 5 is a section on the line 5—5 of 25 Fig. 1,

Fig. 6 is a section on the line 6—6 of Fig. 5.

In the present embodiment of the invention, a base, or fixed member, is provided 30 in the form of a plate, having at one end an opening 2 by means of which it may be suspended, or may be connected with a holding chain, for instance, and at the other end the plate is notched longitudinally, as shown 35 at 3, to provide a wrench, the notch having side walls perpendicular to the bottom of the notch.

At each side of the notch, the edge of the plate is beveled, as shown in Fig. 4, to provide 40 portions which may be used as screw drivers, one of said portions being provided at each side of the plate.

The movable member 4 is pivoted to the plate 1, intermediate to ends of the said 45 member, and one end of this plate 4 is oppositely beveled, as shown in Figs. 1 and 2, to provide a pointed member; that is, the side edges of the plate converge to a point, and the said end of the plate may be used as a 50 paper knife for opening envelops, as a spike for lifting corks, or for manicuring—that is, to clean the finger nails.

The plate 1 has a pin 5 at the end adjacent to the opening 2, against which the 55 point 1 of the member 4 abuts, when the said member 4 has its long axis parallel

with, or substantially parallel with the long axis of the plate 4. The opposite end of the plate 4 is bent upwardly from the plane of the plate 1, as clearly indicated at 6, and the 60 said end has a series of longitudinal extending grooves on its under face, which provide ribs 7 between the grooves, the said ribs being triangular in cross section.

Just beneath the grooves and ribs 7, when 65 the plate 4 abuts the pin 5, there is provided a roughened, or toothed surface 8 on the plate 1. Referring to Figs. 5 and 6, it will be seen that the teeth are arranged in series extending longitudinally on the plate 1, and 70 that when the parts are in the normal position of Fig. 1, the teeth 8 register with the grooves between the ribs 7.

The upward bend of the plate 7 provides a slight space between the ends of the plates 75 1 and 4 at the ribs 7 and the teeth 8, sufficient to permit the entrance of a check between the two plates. When the check has been so placed, with that part which it is desired to deface directly between the ribs 80 and teeth, the lifted end 6 of plate 4 is depressed in any desired manner, as, for instance, by striking with the open hand, to cause the teeth and ribs to emboss the paper. As soon as the pressure on the portion 6 of 85 the plate 4 is released, the said portion will spring upward and the check will be released. The plate 1 has at one side edge and at the end adjacent to the pin 5 a recess 9. This recess, as clearly shown in Fig. 3, has 90 one wall inclined, and the other undercut, to form a pointed lug 10, which will act as a bottle-cap remover. At the opposite side edge, the plate 1 is made straight to provide a rule, and this edge has graduations. 95

In use, when it is desired to deface a check, with the parts in the position of Fig. 4, the check is inserted between the plates 1 and 2, and the upstanding end 6 of plate 4 is depressed.

In order to use the bottle-cap remover, or the pointed end of the plate 4, the said plate is swung to one side to uncover the recess 10, and to bring the point of the plate into convenient position to use. The extent of the 105 swinging will, of course, depend upon the part that it is desired to use.

Referring to Figs. 5 and 6, it will be seen that the teeth 8 are formed on an upwardly offset portion of the plate 8.

I claim:

The device substantially as described,

comprising a baseplate having at one end a pin and having at its other end a roughened surface on its upper face adapted to co-operate in canceling a check, and a plate pivoted between its ends at a point between the pin and the roughened surface of the main plate, and having one end arranged to abut the pin and stop said pivot plate with its other end overlying the roughened 10 face of the main plate, said other end of the

pivot plate being sprung away from the roughened surface and adapted to be pressed thereto, said pivot plate having a roughened surface on its under face directly above the roughened surface of the first plate when the said pivot plate contacts with the stop pin, whereby said pivot plate may be swung aside to permit the proper positioning of a check. 15

JAMES W. PRICE.
